UNITED STATES PATENT OFFICE.

SIGMUND F. KOHN, OF NEW YORK, N. Y.

SMOKER'S UTENSIL.

1,427,303.

Specification of Letters Patent. Patented Aug. 29, 1922.

Application filed May 19, 1920. Serial No. 382,665.

To all whom it may concern:

Be it known that I, SIGMUND F. KOHN, a citizen of the United States, and a resident of New York City, (borough of the Bronx,) in the county of Bronx and State of New York, have invented certain new and useful Improvements in Smokers' Utensils, of which the following is a full, clear, and exact description.

10 Among the principal objects which the present invention has in view are: to provide a convenient article of the character mentioned provided with various accessories desired by smokers; and to cheapen the cost 15 of construction of the article.

Drawings.

Figure 1 is a perspective view of a smokers' utensil constructed and arranged in accordance with the present invention.

Figure 2 is a vertical section thereof.

Figure 3 is a top plan view of the utensil.

Figure 4 is a view of the blank from which one side of the utensil is formed, the 25 broken and dotted lines shown therein, indicating bends in the material.

Figure 5 is a detail view in section showing the cutting blade of the cigar cutting attachment and the spring for supporting the 30 same.

Description.

As indicated in the drawings, the completed utensil is constructed from four side 35 members, each member being integral and stamped out of a single sheet of metal. As seen best in Fig. 4 of the drawings two of these sides are modified slightly, after the blanks such as shown in Fig. 4 have been 40 formed.

Referring to the drawing, and particularly to Fig. 1 thereof, the structure is shaped to form a match box 9, a pedestal 10, benches 11 and 12, and feet 13.

45 As the members are joined, used match repository openings, and cigar extension openings are formed in the structure. Also an ash stripper 16 is formed as extensions of the bench 11 to rest over the openings 15 50 and over the cigar resting tray 17 with which the utensil is furnished in service. The strippers 16 are constructed from tabs 18, the ends whereof are soldered or otherwise rigidly connected or permitted to rest, 55 one upon the other, in disconnected relation and as desired.

A bottom 19 is attached to the match box 9 after the sides have been united, or during the operation of uniting the same, to form supports for the bottom 19.

60 The side members 20 which are cut from the openings 21 in the sides of the match box 9 are turned down, as seen best in Fig. 2 of the drawings, and the said bottom 19 is then placed upon them.

65 As a further support to the structure the severed portions 22, which are removed from the openings 14, support the members 20 and the bottom 19. These elements may be connected by soldering, thereby rendering 70 the structure very rigid, as the portions 22 set back from the sides 9 form box-like structures which reinforce the structure. The ledges 23 prevent the escape of the matches 75 from the box 9, even though the openings 21 are not covered.

As above stated two of the sides 9 are modified, one by mounting thereon, in the pedestal 10, a ferrule 24. The inner edge of the said ferrule is squared to form a cutting edge for operating in conjunction with the knife 25 to operate for severing the ends of cigars. The knife 25 has a handle 26 protruding from the side of the pedestal and extending through the slot 27 therein.

80 As seen best in Fig. 5 of the drawings, the strip 28 which is forced out of the side to form the slot 27, is bent back to support the free end of a spring 29, the coil whereof is wrapped over a pin 30. The opposite end 85 of the said spring is made fast to the blade 25. The strip 28 is preferably fastened to the side of the pedestal adjacent thereto.

85 One of the side pieces is provided with a scratch pad 31. The pad 31 may be made 90 from a separate piece to be structurally united with the side on which it is held. The modified form, however, of the scratch pad is shown in Fig. 4 of the drawings, 95 wherein the section 32 of one of the benches 100 12 is serrated to form a friction surface on which the matches may be ignited.

105 When assembling the side pieces to form the utensil herein described, the blanks shown in Fig. 4 are bent on the lines 33 and 34, to turn inward, the pieces 20 and 22. The pieces 20 as above described when properly disposed rest upon the top edges of the pieces 22. The blanks are then bent on the lines 35, 36 and 37, which when bent, 110 form the benches 11 and 12, which benches are disposed in substantially horizontal po-

sition. When the blanks then bent are connected, the tabs 38 of one side member are inserted in the slots 39 of the opposite member, the tabs are over-turned to draw the 5 members rigidly together. The sections 40 are first pressed to form the bead 41 extending about the structure, and the lower portions are then turned in as seen best in Fig. 2 to form the slide benches 42 to support 10 the sliding bottom 43. The bottom 43 is provided, adjacent the inner edge thereof, with a stop 44.

It is obvious that with the reinforcement to the structure afforded by the members 22, 15 pieces 20 and the bottom 19, the tabs 38 and slots provided therefor are sufficient to hold the structure secure after assemblage. Usually the utensil is dipped or otherwise coated with lacquer or other decorating material which assists in fastening the parts 20 together.

When the utensil is employed the box 9 holds a supply of matches. The openings 14 are intended as entrances to the repository 25 for the said matches after the same have been used. The matches then placed through the openings 14 fall upon the bottom 43, which is closed as shown in the drawings. The lighted cigars may be disposed on the 30 rests 17, the lighted and ash bearing ends of said cigars extending through the openings 15 to be held above the slide bottom 43. As the cigars are lifted from the rests 17 they are wiped against the stripper 16 with 35 the result that the ash is removed from the cigar. When the matches are lighted, the scratchers 31 and 32 are used.

After the utensil has been in service and its is desired to clear the debris, the slide 43 40 is drawn out and whatever has been deposited on the surface thereof, either in the shape of ashes or match-sticks, is wiped off to fall in any receptacle which is intended to receive the same. The stop 44 prevents the total 45 withdrawal of the slide bottom 43 from its guides.

Claims.

1. A smoker's utensil comprising a plurality of full side forming pieces, said pieces being adapted to be united to form a compartment for holding matches in superposed relation; a receptacle for waste matches in netherposed relation to said compartments; said utensil having a plurality of openings for receiving lighted cigars; one of said side forming pieces having a match lighting surface provided thereon; and means for uniting said side forming pieces in service relation.

2. A smoker's utensil comprising a plurality of side forming pieces; means for uniting said pieces permanently in structural relation, said pieces having partially severed 65 portions bent back from the exposed side

thereof to form a bottom for a match container, and a series of bracket supports for said bottom forming pieces, said pieces having edge opening recesses cooperating to form passages opening into the interior of 70 said structure; a removable bottom for said structure adapted for holding the cigar ashes when deposited thereon through said openings; and a series of supports mounted on said structure at the edge of said edge 75 opening recesses.

3. A smoker's utensil comprising a plurality of unit side forming pieces, each of said pieces having partially severed portions to be set back from the exposed surface of said 80 pieces for forming the bottom of a match container, and netherposed brackets therefor disposed thereunder; and a plurality of edge opening recesses formed in said pieces for co-operation to provide openings 85 through which the burnt matches and the ends of cigars may be delivered and extended within the structure, and a sliding bottom for said structure, said bottom being removable for the dumping of said matches and 90 the ashes of cigars which may be deposited on said bottom in service.

4. A smoker's utensil comprising a plurality of unit side forming sheet metal pieces, the sections whereof are shaped to 95 form a pedestal and match receptacle to superposed thereover, said pieces having bracket sections partially severed therefrom and turned back from the exposed surface of said pieces in the structure in perpendicular relation to the sides of said structure, and portions of the structure being inturned to constitute in service the bottom of said receptacle.

5. A smoker's utensil comprising a plurality of side forming pieces having tabs for uniting said side forming pieces, the tabs on each of said pieces being adapted for engaging the edges of the adjacent pieces; a plurality of tabs formed on said pieces in juxtaposed relation to certain openings in the side of the structure, the ends of said tabs being united to form ash strippers for cigars which may rest thereunder; and a plurality of cigar rests mounted on said utensil adjacent said strippers.

6. A smoker's utensil comprising a plurality of unit side forming pieces, said pieces being bent to form benches, the benches formed by each side being independent of 120 the benches formed by the other and separated therefrom for forming corner openings in the utensil for the reception of waste articles, portions of said side forming pieces being shaped to form supports for said 125 utensil; means for permanently uniting said side forming pieces in structural relation; and a removable bottom for said utensil.

7. A smoker's utensil comprising a plurality of unit side forming sheet metal pieces,

- said pieces being shaped to form a pedestal and a match receptacle in superposed relation, portions of said pieces forming the sides of the match holding receptacle being 5 removed by partially severing the center portions of said sides and turning the same back in perpendicular relation to the exposed surface of said pieces below the lower edge of said openings for forming the bottom of 10 said receptacle.
8. A smoker's utensil comprising a plurality of unit side forming sheet metal pieces shaped to form a pedestal and a match holding receptacle in superposed relation to said 15 receptacle; a cigar cutter mounted on adjacent members of said pieces, said cigar cutter embodying an eyelet mounted on one of said members; and a swinging knife pivotally mounted on said member adjacent said 20 eyelet, a spring for normally supporting said knife; and a rest for the free end of said spring, said rest embodying a strip of metal
- partially severed and set back from the exposed surface of one of said side pieces for forming a slot for the extension there- 25 through of said blade.
9. A smoker's utensil in the form of a base and a pedestal supported thereon, the utensil being formed from a plurality of interlocking side blanks constructed so that 30 each side blank constitutes one side of the utensil.
10. A smoker's utensil side blank constructed so as to be bent transversely intermediate its ends to form one side of the comparatively wide base of the utensil and the corresponding side of the comparatively narrow body thereof, said blank having partially severed portions adapted to be bent at an angle with respect to said blank, said blank 35 being further provided with projections and perforations along certain edges.

SIGMUND F. KOHN.
